Primary Examiner — Catherine R Oliver-Garcia(74) *Attorney, Agent, or Firm* — Polson Intellectual Property Law, PC; Margaret Polson(57) **CLAIM**

The ornamental design for a lanyard, as shown and described.

DESCRIPTION

FIG. 1 is a front isometric view of our new design for a lanyard;

FIG. 2 is a front elevation view of FIG. 1;

FIG. 3 is a rear elevation view of FIG. 1;

FIG. 4 is a right side elevation view of FIG. 1.

FIG. 5 is a left side elevation view of FIG. 1.

FIG. 6 is a top plan view of FIG. 1; and,

FIG. 7 is a bottom plan view of FIG. 1.

The dashed lines in drawing depict environmental subject matter and the continued length of the lanyard only and form no part of the claimed design. The dotted lines represent stitching and are claimed.

The break lines disclosed in the drawings indicate that no particular length is claimed and any portion shown between forms no part of the claimed design.
